UNITED STATES PATENT OFFICE.

NICHOLAS N. BARRON, OF NEWARK, NEW JERSEY.

BURIAL CASKET OR COFFIN.

Application filed September 10, 1925. Serial No. 55,473.

This invention relates, generally, to improvements in burial coffins or caskets; and, the present invention has reference, more particularly, to provide a coffin or casket, the structure of which is such that a water or moisture-proof, as well as an air-proof burial-receptacle is provided, so that if decided, it will be unnecessary to use an outside casing or box, or a vault for the same.

The present invention, therefore, has for its principal object the production of a novel and simply constructed burial coffin or casket which may be sealed up so as to provide the same entirely weather and air-proof, so that the coffin or casket while it has the general appearance of the coffin or casket now in general use, still is perfectly water and moisture-proof, so that it will not rot when placed in the ground, and at the same time is also perfectly air-proof, so that the corpse within the coffin or casket will be preserved in its buried condition for a long time.

The invention has for a further object to construct a coffin or casket both the body and lid of which comprise an outer shell of marble, either in the form of slabs, or a plastic composition, an inner shell or lining of fiber, beaver board, or the like, with an intermediate layer of water or moisture-proof material, as tar, wax, asbestos and shellac, to which may be added charcoal, which prevents rotting, and asbestos, which prevents freezing and cracking, the lid being sealed to the body of the coffin or casket before it is placed in the ground.

Other objects of this invention not at this time more particularly enumerated, will be more fully understood from the following detailed description of the present invention.

With the various objects in view, the said invention consists in the novel coffin or casket hereinafter set forth; and the said invention consists, furthermore, in certain other features of construction and in the combinations and arrangements of parts, described in detail in the following specification, and illustrated in the accompanying drawings, in which:—

Figure 1 is a side elevation of a coffin or casket made according to and embodying the principles of the present invention; Figure 2 is a longitudinal vertical section of the same; and Figure 3 is a plan view of the body of the coffin or casket, the lid being represented removed therefrom.

Figure 4 is a sectional perspective view of a portion of said body; and Figure 5 is a transverse vertical sectional representation of fragmentary portions of the body and lid 60 of the coffin or casket, said views being made on an enlarged scale.

Similar characters of reference are employed in the said above described views, to indicate corresponding parts. 65

Referring now to the said drawings, the reference-character 1 indicates a complete coffin or casket showing one embodiment of the principles of the present invention, the body of which comprises an outer shell 2 70 of any suitable thickness, said shell being made of marble in the form of slabs, or other suitably connected pieces of marble, or a mixture of marble-dust and other binding ingredients, all adapted to receive a high polish, to provide a body having an outer ornate appearance. The reference-character 3 indicates an inner shell or lining, preferably of fiber or beaver-board, suitably fitted within said body to provide a space, which is 80 filled with a water or moisture-proof material 4, consisting of a suitable mixture of tar, wax, and shellac, to which may be added asbestos and powdered charcoal, the latter ingredients being used to prevent cracking and freezing, and the charcoal being especially useful to prevent rotting. In a similar manner, the lid of the coffin or casket also consists of an outer shell 5, made of marble in the form of a slab, or other suitably connected piece of marble, or a mixture of 90 marble-dust and other binding ingredients. The lid is also provided with an inner shell or lining 6 of fiber or beaver-board, arranged within said outer shell 5 to provide 95 a space which is filled with a water or moisture-proof material 7 of the nature hereinbefore described.

To provide an air-tight connection between the body and lid of the coffin or casket, 100 grooves or channels 8 and 9 may be provided, for the reception therein of a packing 10 of rubber, or other analogous material which is compressed within said channels or grooves, to provide an air-tight joint when the lid is fastened down upon the body by means of the usual fastening means, as will be understood from an inspection of Figures 2 and 5 of the drawings. 105

Of course, the coffin or casket thus produced may have suitably secured thereto any of the usual carrying means, as 11, and 110

the interior of the body and lid may be suitably lined with any suitable material 12, such as silk, or the like.

From the foregoing description of the present invention it will be seen that I have produced a highly ornate coffin or casket, which is perfectly water or moisture-proof, as well as air-proof, the materials and ingredients preventing cracking and freezing.

- 10 Furthermore, owing to the nature of the outer shells of the body and lid of the coffin or casket, the surfaces thereof can be highly polished and variously finished, so as to provide a highly attractive burial device; and,
- 15 if desired, owing to the novel construction, and the water or moisture-proof elements of the coffin or casket, the same can be placed in the ground, without the usual outer box now employed.
- 20 Of course, I am fully aware, that my present invention is capable of some changes in the general arrangements and combinations of the various parts, without departing from the scope of the present invention as set forth in the foregoing specification, and as defined in the clauses of the claim which are appended thereto. Hence, I do not limit my present invention to the exact arrangements and combinations of the various devices and parts as described in the said specification,

nor do I confine myself to the exact details of the construction of the said parts, as illustrated in the accompanying drawings.

I claim:—

1. A coffin or casket comprising a body 35 and a lid, each consisting of an outer shell of mineral substance and an inner shell of fibrous material arranged to provide a space between them, and a moisture-proof material filling said space, consisting of a 40 mixture of tar, wax, asbestos and shellac.
2. A coffin or casket comprising a body and a lid, each consisting of an outer shell of mineral substance and an inner shell of fibrous material arranged to provide a space 45 between them, and a moisture-proof material filling said space, consisting of a mixture of tar, wax, asbestos, shellac and powdered charcoal.
3. A coffin or casket comprising a body 50 and a lid, each consisting of an outer shell of marble and an inner shell of fibrous material arranged to provide a space between them, and a moisture-proof material filling said space, consisting of tar, wax, asbestos, 55 shellac, and powdered charcoal.

In testimony, that I claim the invention set forth above I have hereunto set my hand this 8th day of September, 1925.

NICHOLAS N. BARRON.
